UNITED STATES PATENT OFFICE.

EDGAR A. EWING, OF CHICAGO, ILLINOIS, ASSIGNOR TO THE GOVERNMENT OF THE UNITED STATES REPRESENTED BY THE SECRETARY OF THE NAVY.

TORPEDO.

Application filed February 1, 1923. Serial No. 616,400.

This invention relates to improvements in torpedoes and more particularly to an apparatus adapted to be associated with the practice-head of a torpedo for making a signal, 5 preferably audible, whereby the torpedo may be located if, for any reason, it should stop and sink during its trial run.

One of the objects of the present invention is to provide a simple and practical mechanism adapted to be installed in the practice head of a torpedo for producing either a continuous or intermittent sound as desired during the entire run and for a relatively long time thereafter whereby the location of the 10 15 torpedo may be determined with any one of the several direction indicator submarine signals now in general use in the Navy.

A further object is to provide a small compact inexpensive device of the above character which will be reliable and efficient in use and operation.

Other objects will be in part obvious and in part hereinafter pointed out in connection with the following analysis of this invention 25 when taken in connection with the accompanying sheet of drawings illustrating one of various possible embodiments of the invention.

In this drawing, 30 Figure 1 is an elevational view partly in section showing the apparatus as installed in a torpedo practice-head.

Figure 2 is a diagrammatic view showing the electrical connection and arrangement of 35 the various parts.

Figure 3 is a sectional view taken substantially along the line 3/3 of Figure 1.

Figure 4 is a sectional view taken substantially on the line 4/4, Figure 1.

40 Figure 5 is a top plan view of the mechanism shown in Figure 1.

Figure 6 is a detail sectional view taken on the line 6/6, Figure 5.

Referring now to this drawing in detail, 45 11 indicates a rubber nipple adapted to be connected to a standard marine receiver 12 having associated therewith a high frequency tuned buzzer 13, a transformer 14 and condenser 15 connected therewith, a 50 source of current is indicated by batteries 16 and 17 which are preferably of standard dry cell type, a switch 18 is provided for controlling the circuit as will hereinafter be explained and an ammeter may be inserted

in the circuit at 20 if so desired for any 55 reason.

This entire mechanism is preferably enclosed within a cylinder 21 as indicated in Figure 1 and the entire device passed through opening 22 in the shell of the practice-head into a well 23 and sealed in place by threaded ring 24. All of these parts are 60 65 preferably of standard equipment and can be purchased in the open market and assembled by any one skilled in the art.

In view of the wiring diagram shown in Figure 2, the push button 18 is preferably located outside of the practice-head for the purpose of testing and a small slide plate may be placed adjacent to the button which 70 75 allows the contact to be made permanent if so desired. This switch is, however, preferably closed hydrostatically when the torpedo sinks to a predetermined depth and in this manner the batteries are conserved because 75 the circuit is automatically broken when the torpedo is taken out of the water after its practice run. This, however, is a mere detail and can be varied to suit the desires of those operating the same. Likewise the type of 80 85 buzzer may be varied either to the intermittent or the continuous type. The intermittent buzzer has certain desirable features in that the sound can be more easily picked up and distinguished from the steady vibration produced by a distant steamer.

It is believed to be unnecessary to go into the type of receivers cooperating with this mechanism, as any one of several types may be used. That type generally known to the 90 service as C tube is perhaps more accurate. This instrument merely comprises a T-shaped tube having rubber bulbs at the ends of the cross of the T and the base of the T is provided with ear attachments and by rotating the T to the right or to the left the proper direction may be easily and quickly determined by the operator.

It will thus be seen that the present invention provides a simple and practical 100 mechanism which may be inexpensively manufactured and assembled and conveniently carried by the practice-head of torpedoes now in general use without material alteration and disarrangement of the other members carried thereby.

Without further analysis, the foregoing will so fully reveal the gist of this inven-

tion that others can by applying current knowledge readily adapt it for various applications without omitting certain features that, from the standpoint of the prior art, 5 fairly constitute essential characteristics of the generic or specific aspects of this invention, and, therefore, such adaptations should and are intended to be comprehended within the meaning and range of equivalency of the 10 following claims.

I claim:

1. In a torpedo, in combination, electrical signal producing means, means in contact with the water in which the torpedo is 15 placed for transmitting the vibrations of said signal producing means to the water and a hydrostatically actuated switch for closing the circuit through said signal means when the torpedo reaches a predetermined depth.
- 20 2. In a torpedo, in combination, a practice-

head, electrical means for producing an audible signal, marine transmitting mechanism associated therewith and a hydrostatically actuated switch for closing the circuit through said signal means when the torpedo 25 reaches a predetermined depth.

3. In a torpedo, in combination, a practice-head, an electrically actuated audible signal mechanism including a transformer and condenser, a radio buzzer connected therewith, a marine receiver, means whereby said audible signal is transmitted to the water in which the torpedo is placed and a hydrostatically actuated switch for closing the circuit through said signal means when the torpedo 30 reaches a predetermined depth.

Signed at Chicago, Illinois, this 7th day of September, 1922.

EDGAR A. EWING.
